HIGH SPEED GRINDING WHEELHEAD

Rolland C. Griffith, Shrewsbury, Mass., assignor to The Heald Machine Company, Worcester, Mass., a corporation of Delaware

Application May 27, 1959, Serial No. 56,106

Term of patent 14 years

(Cl. D37—1)

FIG. 1.

FIG. 2.

FIG. 3.

Fig. 1 is a perspective view of a high-speed grinding wheelhead, showing my new design.

Fig. 2 is a plan view of the wheelhead, and

Fig. 3 is an end view of my wheelhead.

The side not shown is substantially the same as the side disclosed and the end is substantially plane.

I claim:

The ornamental design for a high speed grinding wheelhead, as shown and described.
